UNITED STATES PATENT OFFICE.

ERASTUS E. WINKLEY, OF LYNN, MASSACHUSETTS, ASSIGNOR TO UNITED SHOE MACHINERY CORPORATION, OF PATERSON, NEW JERSEY, A CORPORATION OF NEW JERSEY.

HEEL-BUILDING MACHINE.

Application filed September 22, 1922. Serial No. 589,794.

To all whom it may concern:

Be it known that I, ERASTUS E. WINKLEY, a citizen of the United States, residing at Lynn, in the county of Essex and State of Massachusetts, have invented certain new and useful Improvements in Heel-Building Machines, of which the following is a specification.

This invention relates to heel building machines and more particularly to such machines for producing a low heel-section.

Certain types of heels are built from heel-sections comprising (1) a base lift and a plurality of lifts superposed thereon, all of which are composed of a leather substitute, (2) a so-called leather unit or section comprising one or more lifts of a medium quality of leather, and (3) a top lift of a fine quality of leather. The leather unit varies from one-eighth to three-eighths inches, approximately, in thickness and is usually composed of two or more layers of leather of different grades, or of leather and rubber, preferably secured together by paste. The present invention is particularly useful in building heel-sections or units of this character.

The general object of the present invention is to improve heel lift assembling mechanisms in a manner to provide a machine particularly adapted for building heel-sections for use in manufacturing heels of the character above indicated.

Other objects of the invention are to provide a machine of the character described by means of which the assembling of the lifts in the required order will be insured without the necessity of constant careful attention and thought upon the part of the operator, and to provide an efficient and reliable machine which is of simple and rugged construction and one which is entirely automatic in operation after the component lifts have been supplied thereto.

With the above objects in view, the present invention contemplates the provision, in a machine of the general character above indicated, of an endless carrier, which may conveniently be a rotary turret having a plurality of equally spaced lift-holding recesses or pockets, the number of which is one greater than some multiple of the number of the component layers or lifts to be assembled in each heel-section or unit; means

for advancing the carrier step by step through feed steps equal to the same number of pocket spacings as there are lifts in the heel-section being formed; a number of pasting devices, equal to one less than the number of component lifts in the heel-section, for supplying paste to secure the lifts together; means for discharging the assembled heel-sections from the pockets; and means for receiving the discharged sections and holding them under pressure during the setting of the paste. It is within the scope of the invention to secure the component parts of the heel-section together in any convenient manner by any suitable securing agent, and while paste is preferred, those skilled in the art will recognize that its use is not essential.

In accordance with the illustrated embodiment of the invention, the machine is so constructed as to build heel-sections composed of two lifts. In such illustrated machine a rotary carrier or turret is provided, having five equally spaced lift-holding recesses or pockets, which is rotated intermittently through steps equal to twice the angular distance between the pockets. During periods of rest of the carrier between successive step movements thereof, the carrier is positioned with two adjacent pockets located at two lift receiving stations where one lift is inserted in each pocket by the operator. An automatic pasting device is located at the station occupied by one of the pockets adjacent the receiving stations for applying paste to the lift when at said station, while the pocket at the station next beyond the pasting station is positioned in registry with a tube-like press and a reciprocating plunger is provided for delivering the assembled heel-sections to the press.

While a machine constructed as above described has been selected for illustrative purposes, the invention is not limited to such a machine, but includes within its scope machines adapted to build heel-sections composed of three or more lifts. For example, if a heel-section composed of three lifts is to be built, the carrier is provided with seven lift receiving recesses or pockets and is advanced through steps equal in length to three times the angular distance between the pockets, in such a case, two pasting devices being employed and three lifts being sup-

plied at each period of rest. For building a heel section composed of four layers or lifts, the carrier is provided with nine lift receiving recesses or pockets and is advanced 5 through steps equal in length to four times the angular distance between the pockets, three pasting devices being employed and four lifts being supplied at each period of rest.

19 It will be observed that the description just given of the construction of the machine for building heel-sections of two, three or four lifts relates to a design, in each instance, having the number of lift pockets 15 equal in number to twice the number of lifts in the unit being built plus one. Calling the number of lifts in the unit n , the number of pockets is expressed by the formula $2n+1$. This construction is preferable 20 because with it the feed step is of the minimum length and this results in the greatest output. As previously described, the scope 25 of the invention includes a design in which the number of lift pockets may be any multiple of the number of lifts in the unit, the feed step being correspondingly increased in length. For example, a two lift unit may be manufactured with nine, or $4n+1$, turret 30 pockets, but the feed here must be through four pocket spacings instead of two. Calling m the variable multiplier of the number of lifts in the unit, then the number of pockets to be provided on the carrier may be expressed broadly by the formula $mn+1$. 35 Whatever the number of lift pockets the number of pasting devices would, of course, always be $n-1$.

The present machine, as will hereinafter appear, is so designed that such changes in 40 the construction and arrangement of parts as may be necessary to adapt the machine to make a heel-section comprising more than two lifts, can readily be made without any variation from the principle of opera- 45 tion.

To the accomplishment of the above objects and such others as may hereinafter appear, the features of the present invention consist in certain novel constructions, arrangements and combinations of parts hereinafter described and more particularly pointed out in the appended claims, the advantages of which will be apparent to those skilled in the art.

55 The features of the invention will be readily understood from the accompanying drawings illustrating the preferred form of the invention, in which Figure 1 is a top plan view of a machine constructed in accordance with the present invention; Fig. 60 2 is a view in side elevation, looking from the right in Fig. 1, with the paste pot removed and certain portions of the machine being broken away; Fig. 3 is a sectional view taken 65 on the line 3-3 of Fig. 2; Fig. 4 is a sec-

tional view taken on the line 4-4 of Fig. 3; Fig. 5 is a view in front elevation of a portion of the cement applying mechanism; Fig. 6 is a view similar to Fig. 5 showing the parts in a different position; Fig. 7 is a view 70 in side elevation of the mechanism shown in Fig. 6; Fig. 8 is a detailed view in front elevation of the cement reservoir; Fig. 9 is a view partially in section on the line 9-9 of Fig. 3 and partially in front elevation, showing particularly the tube-like press for holding the assembled heel sections during the setting of the paste; Fig. 10 is a top plan view of the press shown in Fig. 9; Fig. 11 is a detailed sectional view taken substantially on the line 11-11 of Fig. 10; Fig. 12 is a detailed view of a portion of the means for adjusting the size of the press, the view being taken substantially on the line 12-12 of Fig. 9; Fig. 13 is a sectional view of a 80 portion of the rotatable turret, the left half of the view being taken substantially on the line 13^a-13^a of Fig. 1, and the right half of the view being taken substantially on the line 13^b-13^b of said figure; Fig. 14 is a detailed view of the driving clutch taken on the line 14-14 of Fig. 1; Fig. 15 is a detailed view taken substantially on the line 15-15 of Fig. 3; Fig. 16 is a perspective view of a portion of the mechanism for adjusting the 90 size of the press; Fig. 17 is a perspective view of the rigid framework of the press; Fig. 18 is a perspective view showing particularly the supporting bracket upon which the framework shown in Fig. 17 is mounted, 100 Fig. 19 is a perspective view showing the manner of mounting the breast member of the tube press, and should be read with Fig. 16; Fig. 20 is a view, in side elevation, of a portion of the machine adjacent the die 105 illustrating a safety slide which may be employed; Fig. 21 is a plan view, somewhat enlarged, of the parts shown in Fig. 20; and Fig. 22 is a vertical section on the dotted line 22-22 of Fig. 20.

The illustrated machine comprises, in general, a supporting frame 20 (Fig. 2) upon which the various parts of the machine are mounted, a stationary annular feed table 22 (see also Figs. 1 and 3) and 110 a carrier or turret 24, the latter adapted to be intermittently rotated in a horizontal plane just above the central opening in the feed table 22 and having a plurality of lift 115 engaging and alining devices overlying the table and serving in conjunction therewith to provide five equally spaced apart lift receiving pockets 26 (Fig. 1), two of which are located during the periods of rest of the turret at two lift-receiving stations 28 and 120 30, while a third pocket is located at a pasting station 32 and a fourth at a discharge station 34; means, including a feed pawl 36 (Fig. 3) and an oscillatory pawl-carrier disk 38, for rotating the turret 24 to ad- 125 130

vance the lifts step-by-step in a circular path around the feed table; an automatic pasting device 40 (Fig. 1) for applying a coating of paste or cement to the upper face 5 of the lift in the pocket at the pasting station 32; a vertically reciprocating plunger 42 (Fig. 2) arranged above the plane of the turret 24 at the discharge station 34 and adapted to engage the assembled heel section in the pocket at the discharge station 10 and force it downwardly through a lift-shaped opening 44 (Fig. 3) in the feed table; and a tube-like press 46 (Fig. 2) vertically arranged beneath the feed table 22 15 with its upper end closely adjacent the opening 44 to receive the successively discharged heel sections and hold them under pressure during the setting of the paste.

The supporting frame 20 of the machine 20 comprises a base 50 (Fig. 2), a tubular pedestal 52 and a forwardly projecting hollow head 54, all of which are rigidly secured together by means of vertical tie bolts 56 extending through the pedestal 52. The 25 forwardly projecting portion of the head 54 supports a substantially semi-circular bracket 58 (Fig. 3) to which the feed table 22 is rigidly secured by means of screws 60.

The various movements of the operating 30 parts are derived from cams 62, 64, 66 and 68, secured upon a horizontal cam shaft 70 (Figs. 1 and 2) that is journaled in bearings formed within brackets 72 rising from the rear portion of the head 54. The cam shaft 35 70 is driven by a belt 74 which passes over a pulley 76 that is secured to one end of the cam shaft and over a pulley 78 that is loosely mounted upon one end of a horizontal driving shaft 80, the latter being parallel to the cam shaft 70 and being journaled in bearing brackets 82 rising from the base 50. Normally the pulley 78 is connected to rotate with the driving shaft 80 by means of 40 a clutch comprising a clutch member 86 carried by the pulley 78 and a clutch disk 88 that is splined to the driving shaft 80. The shaft 80 may be driven from any suitable source of power through the agency of the usual fast and loose pulleys 90 and 92 at the end of the driving shaft opposite the pulley 78.

The clutch member 86 (Fig. 14) consists of a ring arranged in a vertical plane adjacent the inner side of the pulley 78 and pivotally connected with said pulley by means of a stud 96. Projecting radially from the outer edge of the member 86 at a point diametrically opposite the pivot stud 96 is a lug 98 which is adapted to be engaged by one or the other of a pair of driving lugs 100 projecting laterally from the clutch disk 88. The clutch ring 86 is acted upon by a coiled spring 102, one end of which is secured to the lug 98 and the opposite end 60 to the pulley 78. The tension of the spring 65

102 tends to tilt the clutch ring 86 about its pivot stud 96 and to maintain it in the position in which it appears in Fig. 14, the tilting movement of the clutch ring under the influence of the spring being limited by a 70 stop 104 which projects from the inner edge of the ring, midway between the pivot stud 96 and the lug 98, adapted to engage the hub of the pulley 78. When, however, the lug 98 on the clutch ring is engaged by one 75 or the other of the driving lugs 100 on the clutch disk 88, the clutch ring is tilted against the action of the spring 102 until a stop 106, projecting from the inner edge of the ring, at a point diametrically opposite the stop 104, is brought into engagement with the hub of the pulley 78. With the above described construction, the shock incident to the engagement of the driving lug 100 with the lug 98 is absorbed by the 80 spring 102, and the rotation of the cam shaft 70 is initiated without undue vibration. The noise resulting from the contact of the driving lug 100 with the lug 98 may be reduced or eliminated by means of bumpers 108 of leather or other suitable material which may be secured to the operative faces of the drivings lugs 100.

During normal operating conditions, the 85 clutch members 86 and 88 are maintained in operative engagement, the cam shaft 70 is continuously rotated and the turret 24 is intermittently rotated by means of the feed pawl 36 and the pawl-carrier 38 the latter being, in turn, actuated by mechanism controlled by the cam 64. During each period of rest of the turret, the operator inserts a single lift in each of the pockets at the receiving stations 28 and 30. If for any reason the operator should fail to insert a lift 90 in either of the pockets at the receiving stations, he may interrupt the normal operation of the machine by disengaging the clutch members 86 and 88.

To this end, the clutch disk 88 is adapted 95 to be shifted longitudinally of the driving shaft 80 by means of a crank 112 (Figs. 1 and 2) that is secured to the rear extremity of a horizontal rock shaft 114 and carries a stud 117 which projects into an annular groove 119 in a hub 121 formed upon the clutch disk 88. The rock shaft 114 extends forwardly from the crank 112 and is journaled in bearing brackets 116 on the base 100 50. At the forward end of the rock shaft 114 is secured a foot treadle 118 which extends to a position conveniently accessible to the operator. A coiled spring 120 is secured at its lower end to the treadle 118 and at its upper end to the forwardly projecting portion of the head 54, and tends to maintain the treadle in its raised or inoperative position and to hold the clutch disk 88 in operative relation to the clutch member 86. By depressing the treadle 118, the 105 110 115 120 125 130

operator may shift the clutch disk 88 upon the driving shaft, toward the right in Fig. 1, to disconnect the driving lugs 100 from operative engagement with the clutch member 86 so that the rotation of the cam shaft 70 will be arrested. When the lifts have been properly supplied to the pockets at the receiving stations 28 and 30, the treadle 118 may be released and the spring 120 will then raise the treadle and restore the clutch members 86 and 88 into operative relation.

As best shown in Fig. 13, the rotary carrier or turret 24 comprises five disks 124, 126, 128, 130 and 132, these disks being superposed in co-axial relation and disposed in a horizontal plane with the lowermost disk slightly overlapping the inner edge of the annular feed table 22. The several carrier disks are all rigidly but adjustably secured together and are mounted to rotate as a unit upon the upper portion of a vertical post 134 which extends through central apertures in the carrier disks. As shown in Fig. 2, the post 134 is rigidly secured at its lower end in the forwardly extending portion of the head 54 and is screw threaded at its upper end to receive a nut 136 which engages the uppermost disk 124 to prevent upward displacement thereof. Each lift-receiving pocket or recess 26 is defined by the outer extremities of a pair of lugs 140 and 142 (Figs. 1 and 13) and the opposed extremities of a pair of levers 144 and 146. The lugs 140, of which there are five in number, one for each of the lift pockets 26, project radially from the periphery of the upper carrier disk 124, while the lugs 142, also five in number, project radially from the carrier disk 126 and are offset with respect to the lugs 140, as shown in Fig. 1. There are also five pairs of levers 144 and 146. Each pair of levers 144 and 146 is carried by a pair of arms 148 which project radially from the lower disk 132 and carry at their outer extremities vertical studs 150 upon which the levers are fulcrumed. The outer ends of the levers 144 and 146 are formed with vertically disposed semicylindrical portions 152 (Fig. 1) which, together with depending portions 154 upon the lugs 140 and 142, provide a set of lift-engaging and alining faces which define the lift pockets 26. The opposite ends of the levers 144 and 146 are provided with rounded extremities 155 which are received in similarly shaped peripheral notches 156 in the carrier disks 128 and 130, respectively. As shown, the semi-cylindrical extremities 152 of the levers 144 and 146 are adapted to engage the lateral and breast edges of a lift adjacent the two breast corners thereof, while the depending portions 154 of the lugs 140 and 142 are adapted to engage the curved edge of a lift at points somewhat removed from the rear extremity thereof. By means of the parts just described, the lifts

deposited in the pockets 26 are maintained in definite positions therein and a second lift placed in said pockets will be alined with the first lift. During the step movements of the carrier 24, the lower edges of the lift 70 engaging portions 152 and 154 wipe across the feed table 22 and feed the lifts in a circular path.

To vary the size of the lift pockets 26 to accommodate lifts of different sizes or styles, the two upper carrier disks 124 and 126 may be adjusted radially with relation to each other to move the opposed members of each pair of lift engaging lugs 140 and 142 toward or from the opposed member simultaneously. To this end, the upper carrier disk 124 is provided with a slot 158 (Fig. 1) which is inclined relatively to a radial line extending therethrough and the disk 126 is provided with a slot 160 which is inclined an equal number of degrees in the opposite direction and extends diagonally beneath the slot 158. The slots 158 and 160 are provided with slide blocks 162 severally apertured to receive the shank of a bolt 164, having an elongated rectangular head 166 (Fig. 13) at its lower extremity which is arranged to slide longitudinally in a T-shaped groove 168 in the upper side of the lower disk 132. The upper extremity of the bolt 164 is screw-threaded to receive a nut 170 which bears against the upper slide block 162 and retains it within the slot 158. The downward displacement of the lowermost slide block 162 is prevented by means of a collar 172 which surrounds the bolt 164 beneath said slide block, which rests upon the upper face of the lower carrier disk 132 at opposite sides of the groove 168. Circular apertures 174 are provided in the carrier disks 128 and 130 to receive the collar 172 and these apertures are of sufficient diameter to permit free inward or outward adjustment of the bolt 164 in the groove 168 when the nut 170 is loosened. By thus adjusting the bolt 164 inwardly or outwardly in the groove 168, the blocks 162 are caused to slide obliquely in their respective slots 158 and 160 and the resulting cam action between the edges of said blocks and the side walls of the slots causes the carrier disks 124 and 126 to turn in opposite directions upon the post 134, thus varying the distance between the opposed members of each pair of lugs 140 and 142.

The levers 144 and 146 at each of the lift pockets 26 are adjusted about their fulcrums 150 to vary the relation of their opposed extremities 152 and thus adapted to accommodate lifts of different sizes or styles. To this end, the carrier disks 128 and 130 are provided with slots 176 and 178 which correspond to the slots 158 and 160 in the carrier disks 124 and 126 and which are similarly inclined in opposite directions and are arranged so that

one extends diagonally beneath the other. These slots 176 and 178 are provided with slide blocks 180 through which extends a vertical bolt 182 having an enlarged rectangular head 184 at its lower extremity which is formed to slide longitudinally in a T-shaped groove 186 (Fig. 13), in the upper side of the lower carrier disk 132, and disposed at an angle to the corresponding groove 168 already described. The upper end of the bolt 182 is provided with a nut 188 and a collar 190 is interposed between the nut 188 and the upper slide block 180 to prevent upward displacement of the latter. The lower slide block 180 rests upon the upper face of the lower carrier disk 132 at opposite sides of the groove 186. The two upper carrier disks 124 and 126 are provided with circular apertures 192 into which the collar 190 extends, this construction permitting the nut 188 to be located above the upper carrier disk where it may be conveniently manipulated. By loosening the nut 188, the bolt 182 may be readily shifted either inwardly or outwardly in the groove 186, thus shifting the slide blocks 180 in their respective oblique slots 176 and 178 and varying the relative radial positions of the carrier disks 128 and 130 in the same manner as already described in connection with the carrier disks 124 and 126. After the necessary adjustments have been made to vary the size of the lift pockets 26 in accordance with the size of the lifts to be operated upon, and the nuts 170 and 188 have been tightened, the five carrier disks are rigidly secured together and all rotate in unison as the carrier is intermittently actuated.

During the intervals between the successive step movements of the turret or carrier 24, the latter is locked against rotation to maintain the several lift-receiving pockets 26 stationary in the proper positions relatively to the receiving stations 28 and 30, the pasting station 32 and the discharge station 34. The locking of the turret is effected by means of a stop pin 194 (Figs. 2, 3, 4 and 5) and a holding pawl 196 (Figs. 3 and 15) which engage opposite sides of one of five lugs 198, which are equally spaced apart upon the under side of the lower turret disk 132 adjacent the marginal portion thereof. The stop pin 194 is mounted for vertical sliding movement in a guide-way 200 formed on the bracket 58 and is cam actuated, as will be hereinafter described. The holding pawl 196 is bifurcated at one end to straddle an ear 202 rising from the bracket 58 and is pivotally mounted upon the ends of a stud 204, the middle portion of which extends through the ear 202. The holding pawl 196 is urged upwardly by means of an expansion spring 206 (Fig. 15) the lower end of which is received in a socket in the bracket 58, while

the upper end thereof is received in a socket in the holding pawl. The force of the spring 206 tends to hold the pawl 196 in its upper or operative position, this position being determined by the engagement of a stop face 208 on the pawl with a portion of the bracket 58.

While the turret or carrier 24 is thus locked against rotation, the operator places a single lift in each of the lift pockets 26 at the lift-receiving stations 28 and 30. The lifts to be operated upon may be contained in suitable bins or boxes located within convenient reach of the operator, the bin containing the lifts which are to be placed in the pocket at the station 28 being disposed at the left of the operator, while the bin containing the lifts to be placed in the pocket at the station 30 is located at the right of the operator. Thus the operator may use both hands to insert the lifts simultaneously at the two stations 28 and 30, the lift being inserted at the station 30 with the right hand and the lift at the station 28 with the left hand. At the expiration of the predetermined period of rest of the turret 24, if the two new lifts have been properly placed in the machine, the operator does not depress the stopping treadle 118 and consequently the machine is allowed to continue its normal operation. The turret is immediately unlocked by the retraction of the stop pin 194 and a step movement is imparted to the turret.

The stop pin 194 is actuated by means of a lever 210 (Figs. 2 and 3) which is fulcrumed upon a horizontal rod 212, supported at its opposite ends in the head 54. The forward end of the lever 210 is forked to receive a small roller 214 which is mounted upon the adjacent side of the stop pin 194 near the lower extremity thereof. At its rear extremity the lever 210 is pivotally connected with the lower end of a link 216, the upper end of which is connected to the rearwardly extending arm of a bell crank lever 218. The lever 218 is fulcrumed upon a rod 220 which is secured at its opposite ends in the brackets 72. The depending arm of the bell crank lever 218 carries a cam roll 222 which rides upon the periphery of the cam 68. A short coiled spring 224 which is secured at one end to the forward portion of the lever 210 and at the other end to the under side of the bracket 58, tends to hold the stop pin 194 in its raised or operative position and to hold the cam roll 222 against the cam 68. The cam 68 is designed to effect the retraction of the stop pin 194 just prior to the beginning of each step movement of the turret 24 and to raise the stop pin into operative position in time to limit the extent of said movement by engagement with one of the lugs 198.

The step movements of the turret or carrier 24 are produced by means of the feed pawl 36 which operates just after the retraction of the stop pin 194. As shown in Fig. 3, the feed pawl 36 is pivoted upon a vertical stud 228 on the pawl carrier disk 38 and is adapted to engage with one of the five lugs 198 on the under side of the lower turret disk 132. The feed pawl carrier disk 38 is rotatably mounted upon the post 134 (Figs. 3 and 4) beneath the turret and rests upon a boss 230 rising from the bracket 58. The feed pawl 36 is normally held in operative position, as shown in Fig. 3, by means of a coiled spring 232, one end of which is secured to the rearwardly extending tail 234 on the feed pawl, while its opposite end is secured to a pin rising from the feed pawl carrier disk 38. A stop pin 236 on the feed pawl carrier disk 38 limits the movement of the feed pawl under the influence of the spring 232 and thus determines the operative position of the pawl 36.

The feed pawl carrier disk 38 is oscillated by a horizontal rack bar 238, the teeth of which engage teeth 240 formed on the periphery of the pawl carrier disk 38. The rack bar 238 is mounted to slide in a guide-way formed in the bracket 58. At its rear extremity, the rack bar 238 is connected by means of a link 242 with the lower extremity of a lever 244 which is fulcrumed at its upper end upon the rod 220. The lever 244 is provided with an extension 245, the forward portion 246 of which is offset into the vertical plane of a cam lever 248 which is fulcrumed upon the rod 220. The cam lever 248 carries at its lower extremity a cam roll 250 which traverses a groove in the side of the cam 64. As shown in Fig. 2, the cam lever 248 and the forward extension 246 of the lever 244 are connected by a spring 252, the tension of which tends to hold the lever 244 in the position shown in Fig. 2 in which the rack bar 238 is at the forward limit of its movement and the feed pawl 36 is in readiness to advance the turret 24. This position of the lever 244 is determined by an engagement with the lever of the offset end of a stop arm 254 which is formed integrally with the cam lever 248. With variations in the number of lift pockets on a turret of the same diameter the effective throw of the lever 248 will vary and the spring 252 functions to permit this variation without adjustment.

The cam 64 and the above described mechanism associated therewith is constructed and arranged to retract the rack bar 238 to effect the oscillation of the turret 24 through two fifths of a revolution. This movement of the turret causes two of the lugs 198 to pass above the holding pawl 196. Just prior to the passage of the second lug 198 above the holding pawl 196, the stop pin 194 is

raised into operative position in the path of said lug. When said lug engages the stop pin 194, further movement of the turret 24 is arrested and the holding pawl 196 is forced upwardly into operative engagement with the other side of the lug 198, so that the turret 24 is positively locked against further rotation in either direction. This locking of the turret occurs just before the cam 64 has imparted its full rearward movement to the lever 244 and thereafter the spring 252 expands, thus permitting the completion of the movement of the cam lever 248. This construction insures that the turret 24 will be brought to rest with its pockets accurately positioned at the several stations.

During the operation of the machine, whenever the turret 24 comes to rest between successive step movements thereof, the lift pocket positioned at the station 28 will be empty, the heel-section formerly occupying this pocket having been discharged by the plunger 42 at the preceding cycle of operations. The lift pocket which is positioned at the station 30, however, will contain a single lift, to the upper face of which a coating of paste was applied when said pocket was last positioned at the pasting station 32, i. e., two steps of the turret prior to the last step. After each step movement of the turret, as already described, the operator places a single lift in each of the pockets at the receiving stations 28 and 30, the lift placed in the pocket at the station 30 being superposed upon the freshly pasted lift at that time occupying said pocket. Consequently at the next step movement of the turret 24, the heel-section comprising the two lifts which have been assembled in the pocket at the station 30 will be carried beyond the pasting station so that the upper lift will not be coated with paste and said heel-section will be brought to rest beneath the plunger 42 at the discharge station 34 in readiness to be discharged into the press 46. During this step movement of the turret, the single lift in the pocket at the station 28 will be positioned at the pasting station 32 in readiness to be operated upon by the pasting device 40 which applies a coating of paste to the upper face of the lift.

The pasting device 40 comprises, in general, a paste pot 258 (Figs. 1, 5, 6 and 7); an oscillating paste pad 260, which, during each step movement of the turret, is moved into position above the paste pot where it receives a coating of paste upon its lower face and which then moves into position above the lift pocket at the pasting station where, after the turret comes to rest, it applies the paste to the upper face of the lift in said pocket; a horizontal paste plate 262 adapted to be lowered into the paste in the paste pot 258, and thereafter to be raised into contact with the paste pad 260 to transfer a limited

amount of paste to the latter; and an atmospheric pressure controlled or so-called barometric feeding reservoir 264 for replenishing the supply of paste in the paste pot 258.

5 The paste pot 258 consists of a shallow rectangular receptacle or chamber which is secured to the bracket 58 by means of bolts 266 (Fig. 1) which extends through laterally projecting ears on opposite sides of the paste pot and are threaded into said bracket. The paste pot is open at the top to permit the entrance of the paste pad 260.

10 The paste pad 260 which is constructed of suitable absorbent material, is carried by a block 270 which is secured to the lower side of a flat horizontally disposed supporting head 272. The pad 260 and the block 272 are of a size and shape corresponding to that of the lifts or blanks being operated upon to permit the pad to enter the pockets 26. The paste pad 260 is swung back and forth between a paste-applying position above the lift pocket at the pasting station and a paste-receiving position above the paste pot 258. In order that the paste pad shall be properly positioned to receive the paste from the paste plate 262 and to apply it to the heel lifts, provision is made for maintaining the pad at all times in a horizontal plane. To this end, as shown in Figs. 5 and 7, the paste pad supporting head 272 is carried at the lower end of a stem 274 which is pivotally connected by means of studs 276 and 278 to the outer ends of a pair of arms 280 and 282, which are rigidly secured to a pair of horizontal rock shafts 284 and 286, respectively. The rock shafts 284 and 286 are journaled in suitable bearings formed in one of two upright frame members 288 which rise from opposite sides of the paste pot 258. At the opposite ends of the rock shaft 284 from the arm 280 is secured a pinion 290, and to the opposite end of the rock shaft 286 from the arm 282 is secured a pinion 292. Meshing with the pinions 290 and 292 are idler pinions 294 and 296, respectively, and meshing with both of the idler pinion is a rack 298 which extends vertically through an opening 299 (Fig. 3) in the bracket 58 and is mounted for sliding movement in a guideway 300 at the outer side of the adjacent frame member 288. The rack 298 is adapted to be reciprocated to rotate the arms 280 and 282 in unison to swing the paste pad 260 back and forth between the paste-applying and paste-receiving positions. By virtue of the parallel relation of the arms 280 and 282, the paste pad is maintained at all times in a horizontal plane. The construction of the means for actuating the paste pad is such that as the pad is moved from one extreme position to another, it is lifted clear of the adjacent side wall of the paste pot 258.

65 The rack 298 is raised by means of a ver-

tically reciprocating actuator segment 304 (Figs. 2, 3 and 4) which is disposed in a horizontal plane beneath the bracket 58 and partially surrounds the forwardly projecting portion of the head 54. The rack 298 is lowered as the actuator segment is lowered by the action of a coiled spring 306 (Fig. 6) one end of which is secured to one of the brackets 288, while the other end is secured to a lever 308, one end of which engages the upper extremity of the rack 298. The opposite end of the lever 308 is pivoted upon a stud 310 projecting from the side of the adjacent bracket 288.

70 The actuator segment 304 is guided for vertical movement by means of three guide rods 312 (Figs. 2, 3 and 4) depending upon the bracket 58. The actuator segment 304 is raised and lowered by means of a pair of bell crank levers 314 which are fulcrumed at opposite sides of the forwardly projecting portion of the head 54 and a third bell crank lever 316 which is fulcrumed upon the rod 212. The forwardly extending arm of each pair of bell crank levers 314 engages between upper and lower lugs 318 projecting inwardly from opposite sides of the actuator ring, while the forwardly projecting arm of the bell crank lever 316 engages between upper and lower rearwardly projecting lugs 320 upon the central portion of the actuator segment (Fig. 2). The downwardly extending arms of the three bell crank levers are connected by means of links 320 to the lower ends of three arms 322 secured to a horizontal rock shaft 324 which is journaled in bearings in the rear portion of the head 54. The rock shaft 324 is actuated by means comprising an arm 326 (Figs. 2 and 3) secured to the rock shaft, a link 328, the lower end of which is pivotally connected with the arm 326, and a bell crank cam lever 330 having a rearwardly extending arm pivotally connected to the upper end of the link 328. The cam lever 330 is fulcrumed upon the rod 220 and is provided with a downwardly extending arm carrying a cam roll 332 which travels in a groove in the side of the cam 62. The cam 62 is designed to effect the raising and lowering of the actuator segment 304 to actuate the paste pad 260 so that a coating of paste will be applied to the blank which is positioned at the pasting station 32 during the period of rest of the turret 24 at each cycle of operations of the machine.

75 80 85 90 95 100 105 110 115 120 125 130

By means of the above described construction and arrangement of the bracket 58 and the actuator segment 304, the required number of pasting devices 40 may be readily attached to the machine and actuated for the purpose of adapting the machine to build heel-sections comprising three or more lifts or layers. For example, in building a heel-section composed of three layers or lifts, two pasting devices will be provided, while

in building a heel-section composed of four lifts, it will be necessary to provide the machine with three pasting devices. These pasting devices may be located upon the bracket 58 in the proper positions relatively to the seven or nine pockets 26, as the case may be, when the latter occupy their positions of rest. Suitable openings corresponding to the opening 299 will be provided in the bracket 58 to permit the passage therethrough of additional racks similar to the rack 298 for actuating the paste pads of the several pasting devices. In whatever radial position said racks may be located, their lower extremities will rest upon the actuator segment 304 so that they will be raised thereby without requiring any change whatever in the segment or its actuating means.

When the paste pad 260 occupies the position in which it appears in Fig. 6, a coating of paste is supplied thereto by means of the paste plate 262. After each engagement of the paste pad 260 with the paste plate 262, the paste plate is lowered into the paste in the paste pot 258 and then raised again into position for engagement with the paste pad after the pad has transferred the paste to the lift at the pasting station. To this end, the paste plate 262 is carried at the lower end of a vertical rod 336 which is mounted for vertical sliding movement in guideways 338 formed at the inner side of one of the frame members 288. The rod 336 is acted upon by a spring 340 which is coiled about the rod and is interposed between the upper guideway 338 and a collar 342 which is secured to the rod 336. The force of the spring 340 tends to lower the paste plate 262 into the paste in the paste pot 258. The paste plate is raised into position for engagement with the paste pad 260 by means comprising an arm 344 which is secured to a horizontal rock shaft 346 that is journaled in bearings in the frame members 288, the arm 344 being provided with a laterally projecting pin 248 which enters a transverse notch 350 in the lower portion of the rod 336. The rock shaft 346 is actuated to oscillate the arm 344 by means of a cam lever 352 which is secured at its lower end to the rock shaft 346 and carries at its upper end a cam roll 354 which rides upon the periphery of a cam disk 356 that is secured to the shaft 286. The cam 356 is so designed that when the paste pad 260 is positioned, as shown in Fig. 5, in readiness to apply paste to a lift at the pasting station, the spring 340 will maintain the paste plate 262 in its lowermost position in which it is submerged in the paste pot but as the paste pad approaches the paste receiving position in which it appears in Fig. 6, the paste plate 262 is raised into position to be engaged by the pad and apply a coating of paste thereto.

In order that the lifts at the pasting sta-

tion may be prevented from adhering to the paste pad 260 and thus being raised from the pockets 26, as the pad swings toward its paste receiving position, means is provided for stripping the lifts from the paste pad. To this end, a pair of stripper pins 360 are mounted to slide vertically through guideways which extend through the paste pad 260, its supporting block 270, and the carrier plate 272. The stripper pins 360 depend from opposite ends of a horizontal supporting bar 362 which is carried at the lower extremity of a vertical plunger 364, the latter being mounted for sliding movement in a bore 366 provided in a lateral enlargement in the stem 274. The plunger 364 is urged downwardly by a coiled spring 368 which is confined within the bore 366, its lower end engaging the plunger 364 and its upper end bearing against a screw 370 which is threaded into the upper end of the bore 366 and may be turned to vary the compression of the spring. Normally the supporting bar 362 is maintained in contact with the upper face of the paste pad support plate 272 by the force of the spring 368. The length of the stripper pins 360 is such that when the supporting bar 362 is thus positioned, the lower extremities of the stripper pins project below the lower face of the paste pad, as shown in Figs. 6 and 7. When the paste pad is brought into engagement with a lift in the pocket at the pasting station, the spring 368 yields under pressure on the stripper pins so that the paste pad may come into contact with the lift, as shown in Fig. 5. As the paste pad is raised after applying a coating of paste to the lift, the stripper pins are moved downwardly relatively to the pad by expansion of the spring 368 and the pasted lift is thus stripped from the paste pad. When the paste pad is moved into engagement with the paste plate 262, the lower ends of the stripper pins 360 project through openings 372 (Figs. 1 and 7) in the paste plate.

The paste reservoir 264 comprises a cylindrical tank which is vertically disposed and is bolted to the outer side of one of the brackets 72, as shown in Fig. 1. The closed upper end of the reservoir 264 is provided with a cover 376 which may be removed for the purpose of filling the reservoir. A plurality of cocks 378 at the bottom of the reservoir are provided with manually operable valves for controlling the outflow of the paste. By means of the several cocks 378 the reservoir is adapted to be connected with two or more paste pots for the purpose of adapting the machine to produce heel sections composed of three or more layers or lifts. In the illustrated machine which is provided with but a single pasting device, one only of the cocks 378 is utilized, the others being closed as indicated in Fig. 8, 130

As shown in the drawings, paste is conveyed to the paste pot 258 through a conduit comprising a flexible tube 380, and a short vertical pipe 382 (Fig. 7). The upper end 5 of the tube 380 is connected with the cock 378 which is shown in open position in Fig. 8. The pipe 382 is rigidly secured to the outer side of one of the frame members 288, and the upper end of said pipe is connected 10 with the lower extremity of the tube 380. The lower portion of the pipe 382 extends downwardly a short distance into a laterally extending portion 384 of the paste pot 258, as shown in Figs. 1 and 7.

15 In order that the flow of the paste from the reservoir to the paste pot 258 may be controlled by atmospheric pressure, all joints in the reservoir are made air tight and the cover 376 fits tightly so that air is 20 prevented from entering the reservoir except through the cock which is connected with the paste pot. As soon as the supply of paste in the paste pot rises above the lower end of the pipe 382, the paste seals the opening 25 at the lower end of the pipe against the entrance of air and no paste will flow from the reservoir into the paste pot. When the paste in the paste pot 258 has been so depleted that the level of the paste falls below 30 the end of the pipe, paste will flow from the reservoir into the paste pot until the lower end of said pipe is again sealed. In this way, a substantially uniform quantity 35 of paste is maintained in the paste pot.

40 After a lift has received a coating of paste at the pasting station 32, the next step movement of the turret carries the lift to an idle station between the receiving station 28 and the discharge station 34; the second step movement of the turret brings said lift to the receiving station 30 where a new lift is superposed by the operator upon the pasted lift; while at the third succeeding step movement of the turret the two superposed lifts 45 are brought to the discharge station 34 where they are located beneath the plunger 42 and above the tube press 46. The plunger 42 operates to force the lifts downwardly through the opening 44 in the table 22 and 50 into the press 46.

55 As shown in Fig. 3, the opening 44 in the table 22 is formed within a plate or die 388 consisting of two sections normally arranged in butting end-to-end relation, as shown in Fig. 3. The sections of the die 388 fit into a shallow recess 392 in the upper face of the table 22 with their upper faces flush with the upper face of the table. One of the die sections is rigidly secured to the table, 60 while the other die section is secured to the table by means of screws 394 which extend through slots 396 in said section and are threaded into the table. The construction and arrangement of the slots 396 and of the 65 recessed portion of the table 22 is such as to

70 permit edgewise movement of one section toward and from the other. The adjustable section is yieldingly pressed toward the fixed section by means hereinafter to be described, this arrangement facilitating the downward passage of the lifts therethrough.

75 The plunger 42, by means of which the completed heel sections are removed from the pockets 26 as the latter are positioned at the discharge station 34 and are loaded into the press 46, is mounted for vertical reciprocation in a guideway formed in a bracket 400 (Fig. 2) which rises from the rear of the bracket 58. The plunger 42 is reciprocated by means of a cam lever 402 80

which is pivotally mounted upon the rod 220, the forwardly extending arm of said lever having a head, shaped to seat within a vertical slot near the upper extremity of the plunger 42. (See Figs. 1 and 2). The upper and lower walls of the slot form bearings for the head of the lever 402 which is rounded, as shown, readily to rock in said slot. The cam lever 402 is provided with a 85 downwardly extending arm which carries a cam roll 408 that traverses a groove in the side of the cam 66. The cam 66 is designed to effect a reciprocation of the plunger 42 at each cycle of operations of the machine so that an assembled heel section will be 90 discharged from the turret and loaded into the press 46 after each step movement of the turret. The heel press 46 consists of a tube-like structure comprising an elongated vertical breast member 412 (Figs. 9 and 10) 100

stationarily supported and adapted to engage the breast edges of the heel sections, and six elongated vertical side members, three of which, indicated at 414, are adapted to engage the curved edges at one side of 105 the heel sections, and the other three of which, indicated at 416, are adapted to engage the curved edges at the opposite side of the heel sections. The side members 414, 416 are movable relatively to each other 110 and are spring pressed inwardly to frictionally resist the passage through the press of the heel sections. By reason of this frictional resistance, the operation of the loading plunger 42 results in transmitting a 115

succession of pressure impulses to the column of heel sections in the press 46 so that said sections are firmly pressed together and are held under continuous pressure during the setting of the paste. Means is also provided, as will hereinafter appear, for adjusting the side members 414, 416 inwardly or outwardly to vary the cross sectional area of the press to accommodate heel sections of different sizes.

120 All of the side members of the press are carried by a frame which is indicated generally at 418 in Fig. 17. The supporting frame 418 comprises upper and lower horizontal arms 420 which are curved to par- 125

tially encircle the press and a vertical web 422 connecting one extremity of the upper arm 420 with the corresponding extremity of the lower arm 420. The supporting frame 418 is rigidly but removably secured to a bracket 424, best shown in Fig. 18, supported on the pedestal 52 and having two outwardly extending arms 426 for supporting the frame 418.

Although the side members of the press are adjustable transversely to vary the size of the press, the range of adjustment of these members is necessarily limited and in order that heel sections larger or smaller than those which the press may be adjusted to accommodate may be operated upon by the machine, it is contemplated the entire press 46 shall be removable as a unit in order that other presses may be interchangeably received in the machine, these presses being adapted for adjustment to accommodate either larger or smaller heel sections than those which may be accommodated by the press which has been removed.

To this end the press supporting frame 418 is removably secured to the bracket 424 in the following manner. As shown in Fig. 17, the press supporting frame 418 is provided with a pair of ledges 428 which severally project laterally beyond the web 422 at the opposite side thereof from the curved portions of the arms 420 and these ledges 428 are adapted to rest upon the arms 426 of the bracket 424. The frame 418 is secured to the bracket 424 by means of taper pins 430 (Fig. 9), two of which are provided in the upper ledge 428 and one in the lower ledge 428. The taper pins 430 are seated in taper openings in the ledges and are arranged with their lower extremities extending beyond said ledges and projecting into tapered holes 432 in the arms 426 of the bracket 424.

To facilitate the attachment of the press to the machine or its removal therefrom, a stem 434 rises from the end of each taper pin 430 and extends through an aperture in a bracket 436 which is secured to the corresponding arm 420 of the frame 418. Each taper pin 430 is normally held in the position in which they appear in Fig. 9 by means of a spring 438 which is coiled around the stem 434 between the upper end of the pin 430 and a shoulder formed on the bracket 436. Each stem 434 is provided with a knurled head 440 by means of which the taper pins 430 may be raised to lift them out of the openings 432 in the bracket 424 to permit the removal of the press from the machine. To latch the taper pins 430 in their released positions, a small pin 442 projects laterally from the upper end of the taper pin and when the taper pin has been raised clear of the hole 432, it may be turned by means of its knurled head 440 until the

pin 442 enters a notch 444 in the bracket 436. The taper pin will then be held in its released position until the knurled head 440 is turned in the opposite direction.

The side members 416 of the press comprise elongated flat bars, each of which is rigidly secured to the inner ends of a pair of upper and lower supporting arms 448 and so arranged that the inwardly facing longitudinal edges of the bars are adapted to engage the lateral edges of the heel-sections. The three pairs of supporting arms 448 are loosely mounted upon three vertical rods 450 (Figs. 9, 10 and 17) which are rigidly secured to the upper and lower arms 420 of the bracket 418. The rods extend between said arms 420 and their upper ends project above the upper arm 420, as shown in Fig. 17. The upper side member supporting arms 448 rest upon the upper press frame arm 420, while the lower arms 448 rest upon the lower press frame arm 420. The side members 414 are identical in construction to the side members 416 and each of said side members is rigidly secured to the inner ends of a pair of upper and lower supporting arms 452. There are three pairs of arms 452 and each pair is loosely mounted upon one of the rods 450 above the arms 448 (see Fig. 11). The uppermost of each pair of arms 452 rests upon a slotted cam segment 454 (Figs. 11 and 12) which is interposed between the hubs of said arms and the hubs of the uppermost of the arms 448 and which is utilized for the purpose of adjusting said arms inwardly or outwardly, as will be hereinafter explained. The lowermost of each pair of arms 452 rests upon a slotted cam segment 456 (Fig. 9) which is identical in construction to the cam segment 454 and is interposed between the hubs of said arms and the hubs of the lowermost of each pair of arms 448. The segment plate 456 is actuated concurrently with the cam segment 454 to secure the inward or outward adjustment of the side members of the press.

The breast member 412 consists of a T-bar arranged with its cross web facing toward the interior of the press toward the side members 414 and 416 in a position to engage the breast edges of the heel sections, and is provided with upper and lower laterally projecting bosses 458 (Figs. 10 and 19). To these bosses are pivotally connected the substantially vertical arms of a pair of bell-crank levers 460. The function of these bell-crank levers will presently be explained and they are referred to at this time because the breast member 412 is supported on the frame 418 by studs 462 on which the bell-cranks are fulcrumed.

All of the six side members 414 and 416 of the press are forced inwardly by means of a plurality of coiled springs 464 which

are wrapped around the side members intermediate the upper and lower ends of the press. As shown in Fig. 10, the opposite ends of the spring 464 are secured to the 5 breast member 412. The tension of the springs 464 forces the side members of the press inwardly and normally holds them with their upper extremities in engagement with a depending flange 466 on the under 10 side of the plate or die 388. As shown in Fig. 9, the upper ends of the side members are beveled slightly to conform to a corresponding bevel of the outer face of the flange 466. The flange 466 limits the inward 15 movement of the several side members of the press and thus determines the size of the press in accordance with the size of the blanks which are to be operated upon. If it is desired to operate upon blanks of a 20 different size, the die 388 is removed from the machine and replaced by another die having an opening corresponding in size to the size of the blanks to be operated upon.

To prevent the collapse of the press upon 25 the removal of the die 388 and to obviate the resulting difficulty in adjusting a new die in the machine with its flange 466 properly positioned to limit the inward movements of the side members 414 and 416 of the press, 30 means is provided for opening up the press by moving the side members outwardly and for maintaining them temporarily in their opened position. The means for moving the side members outwardly comprises the 35 cam segments 454 and 456 (Fig. 9) already referred to, manually operated actuating mechanism interconnecting said segments, and a latch 470 (Figs. 2, 9 and 16) for cooperating with said mechanism. As described, the cam segments 454 and 456 rest upon the hubs of the adjacent arms 448 which support the side members 416 of the 40 press. As shown in Fig. 12, each of the cam segments is constructed with an elongated arcuate slot 472 through which the vertical rods 450 extend, the slot 472 being of sufficient length to permit longitudinal edge-wise movement of the cam segment in an 45 arcuate path determined by the contour of the slot. Each cam segment is provided with three actuating lugs 474 which project inwardly from the inner edge of the segment and with three actuating lugs 476 severally 50 projecting from the other edge of the segment. The lugs 474 are so arranged that when the cam segment is shifted in the direction of the arrow in Fig. 12, the lugs are brought into engagement with three studs 478 which depend from laterally off-set portions of the arms 452 and operate to swing the arms in a counter-clockwise direction to move outwardly the side members 414 of the press. The actuating lugs 476 are severally 55 provided with inclined cam faces 480. When the cam segment is shifted as above

described, the cam faces 480 engage with three studs 482 severally rising from three arms 484 which are formed integrally with the arms 448 and are so disposed in relation thereto as to constitute bell crank levers, 70 as clearly shown in Fig. 10.

The cam segments 454 and 456 are shifted for the purpose of opening or closing the side members of the press by means of a pair of bell crank levers 486 (Figs. 9 and 16) which are fulcrumed upon studs 488 carried by the arms 420 of the press supporting frame 418. The upwardly extending arms of the bell crank levers 486 are severally provided with rolls 490 which project into 80 notches 492 (Fig. 12) severally formed in the cam segments between one of the lugs 476 and a lug 494 which projects from the cam segment at one side of said lug 476. The two substantially horizontal arms of the bell crank levers 486 are connected by means of a vertical link 496 and the lower bell crank lever 486 is provided with a handle 498 by means of which both bell crank levers 85 may be actuated in unison by the operator. By lifting the handle, the bell crank levers will be rocked and the cam segments shifted in a direction to move the side members of the press outwardly. The side members of the press are temporarily maintained in 90 their opened position by means of the latch 470, the lower extremity of which is pivoted to the upper arm 420 of the press supporting frame 418. To this end the latch 470 is normally held by gravity in the position in 95 which it is indicated in Fig. 16 with one edge face of the latch in engagement with an extension 500 of the horizontal arm of the upper bell-crank lever 486. When the handle 498 has been lifted to its uppermost position, the extension 500 is raised above a shoulder 502 on the latch 470, whereupon 100 said shoulder swings into position beneath said extension, thereby preventing the return of the bell crank levers 486 to their normal positions and consequently latching in their open position the side members of the press. The latch 470 is provided with an upward extension 504, by means of which 105 it may be manually tripped to permit the springs 464 to move said side members of the press inwardly until their movement is arrested by the flange 466 upon the die 388. 110

In order that the breast member 412 of the press may be moved outwardly concurrently with the side members 414 and 416, the horizontal arms of the bell-crank levers 460 are connected by means of a vertical link 506 (Figs. 2 and 19) and the lowermost of said bell-crank levers is provided with a third arm 508 which is connected by a link 510 with the downwardly extending arm of a bell-crank lever 512 (see also Fig. 16). The bell-crank 512 is pivotally mounted upon the 115 lower arm 420 of the press supporting frame 120

418, and is provided with a forwardly extending arm having an open ended slot therein through which extends a pin 514 carried by a bifurcated extension at the lower 5 extremity of the link 496. By means of this construction, when the handle 498 is lifted, the breast member 412 will be swung outwardly concurrently with the outward movements of the side members 414 and 416 due 10 to the forward pull on the link 510. The latch 470 thus serves to hold all seven of said members in their opened or outermost positions. When the side members of the press have thus been swung outwardly and 15 latched in their outermost positions, the die 388 may be removed and the new die of a different size substituted therefor. Thereafter, when the latch 470 is tripped, all of said members are moved inwardly concurrently 20 through the agency of the springs 464 until their upper ends are brought into engagement with the flange 466 on the lower side of the die then in position. The press is thus adjusted in accordance with the size 25 of the heel sections which are to be built.

In removing the press from the machine, the handle 498 is first lifted to move the side members of the press outwardly until the latch 470 becomes operative to lock said members in their outermost positions against the force of the springs 464. The taper pins 430 are then lifted permitting the entire 30 press to be readily detached as a unit from its supporting bracket 424. A new press 35 may be readily placed in operative position in the machine after the side members of the press have been locked in their outermost positions and the taper pins 430 have been lifted and held in their uppermost positions.

40 The heel-section pressing and delivering mechanism which has been described in detail is not claimed herein except in combination with the heel-section assembling mechanism, since this mechanism forms the subject-matter of a divisional application Ser. No. 46,001, filed July 25, 1925.

It has heretofore been explained how the lift receiving pockets 26 may be adjusted as to size by varying the relation of the levers 50 144 and 146 to the lugs 140 and 142 (see Figs. 1 and 13). While the adjusting mechanism described is accurate and will cause the levers and lugs to grip and hold lifts dinked accurately to size, those skilled in the 55 art of making heels will understand that at times the lifts will not be gripped because of some imperfection, an inaccurate dinking, or careless sorting. Such lifts will be carried over the feed table 22 by the rotation of the carrier or turret 24, but in the machine illustrated in Figs. 1, 2 and 3 there is danger 60 that such loosely held lifts will fall from the pocket into the die as it traverses the die opening 44 in passing from the pasting sta-

tion 32 to the station at the left of the die 65 opening.

To overcome this difficulty it is proposed to temporarily close the die opening during the period of time that a pocket holding a single pasted lift is passing thereover, or, in 70 a machine for making heel-sections of three or more lifts during the times when incomplete heel-sections are caused to pass over the die opening. A mechanism having this 75 function is illustrated in Figures 20 to 22.

The means employed to close the die opening is a horizontally arranged cover plate 520 adapted to slide in a way formed for its reception at the base of the bracket 400 which carries the guide for the ejecting plunger 42. To this end the frame 20, adjacent the rear edge of the feed table, is provided with a channel member 522 (Fig. 22) on which is bolted a cap piece 524. The cap piece has a central portion 525 which depends in the channel and is of such proportions as to leave a space between its lower face and the channel member equal to the thickness of the plate 520. The upper face of the cap piece is faced and supports the usual bracket 400 which is shortened sufficiently to maintain the guide for the ejecting plunger 42 in the same position as shown in Fig. 2. The bracket 72 which supports the cam shaft 70 and bell-crank hanger rod 220 is unaltered, and in Fig. 20 the bell-crank 402 for operating the plunger 42 is shown but its operating cam is omitted. Both arms of the bell-crank 402 are embraced by the forked upper end 526 of a lever 528 pivoted at 527 on the depending arm of said bell-crank. The fork 526 is connected at its upper end by a cross pin 529 which carries a central roll 530 (Fig. 21). A spring 532 attached to said pin 529 and to a pin 534 on the depending arm functions to maintain the roll 530 in contact with the bell-crank. As the bell-crank 402 oscillates, the lever 528 is constrained to oscillate with it. The movement thus imparted to the lower end of the lever is transmitted to the slide plate 520 through a link 536 connecting the lever to the rear end of a central rib 538 extending longitudinally of the plate at its upper side. The central part 525 of the cap piece 524 is provided with a slot 540 (Fig. 22) which receives the rib 538 and their engagement serves to guide the plate in its movement toward and from the die opening.

In operation, as the plunger 42 rises, to permit rotation of the lift carrier 24, the bell-crank 402 acts to swing the lower part of the lever 528 to the left, in Fig. 20, thus advancing the cover plate 520. In Figs. 20 and 21 the plate 520 is shown as advanced part way to its final position when the die opening is closed. When the plunger 42

descends to eject a heel-section into the tube press 46, the plate 520 is simultaneously withdrawn from the die opening. The spring 532 maintains the roll 529 in contact with the bell-crank 402 while the cover plate is being advanced. On the withdrawal of the cover plate a lug 539 on the rib 538 stops the rearward movement by engaging a stop 541 at the rear end of the slot 540. The continued downward movement of the plunger thereafter merely stretches the spring 532.

The control of the cover plate by the means for operating the plunger insures a proper time relation of the two movements and effectually provides for a retention of the partly completed heel-sections in the pockets of the carrier 26 as they pass over the die opening.

As the pasted heel-sections are successively loaded into the press by the loading plunger 42, they are frictionally held between the several side and breast members of the press and their passage through the press is resisted thereby. As a result the heel-sections are continuously subjected to pressure during their advance through the press. The length of the press is such that when the heel-sections finally emerge from its lower end the paste has become set so that the component lifts or layers of the heel-sections are firmly secured together without the necessity of nailing.

By varying the number of lift pockets or recesses in the turret 24 and the number of lift receiving stations and pasting devices, and by varying the extent of the step movements of the turret, all as hereinbefore described, the present machine may be adapted to produce heel-sections composed of three or more lifts.

In each case where the number of pockets is one more than twice the number of lifts in the heel-section to be produced, and the distance traversed by a pocket at each step of the turret is always through the same number of spaces between pockets as there are lifts in said heel-section. This results in a complete heel-section being produced and ejected into the tube press after a number of turret steps, in each case, equal to one less than the number of pockets, and thereafter a complete heel-section is formed and ejected at each succeeding step so long as the receiving pockets are supplied with lifts.

In order to prevent partially completed heel-sections from being delivered to the tube press, the operator, in the five pocket form of the machine, will for the first three steps of the turret place a lift only in the pocket at the receiving station 28. After the third step of the turret the first lift inserted at 28 will be delivered to the pocket at the receiving station 30, the second lift will be delivered to the station at the left of the ejecting station 34, and the third lift will be at the

pasting station 32. Lifts are now placed in both pockets at receiving stations 28 and 30, thus completing the lift section at 30 which is transferred to the ejecting station and forced into the tube press at the next, or 70 fourth turret step. By placing a lift in each pocket at stations 28 and 30 at each period of rest thereafter, a complete heel-section is forced into the tube press at each succeeding step of the turret. In each case 75 the pocket which delivers directly to the tube press is not supplied with a lift until the turret has taken enough steps to cause lifts placed in the other pockets to be delivered thereto in sufficient number that the 80 addition of one lift will complete the heel-section to be produced, i. e. not until the turret has been primed.

While it is preferred to employ the specific construction and arrangement of parts 85 herein illustrated and described it will be understood that such construction and arrangement is not essential except so far as defined in the appended claims, and may be variously changed or modified within the 90 skill of the artisan without departing from the spirit and true scope of the invention.

What is claimed as new, is:

1. A heel building machine for forming heel-sections of at least two lifts having, in 95 combination, a frame providing a number of lift-receiving stations equal to the number of lifts in the heel-section and a discharge station; a conveyer provided with a number of lift-holders equal to one more than a 100 multiple of the number of lifts in the heel-section to be formed, an equal number of said holders registering with said receiving and discharge stations when the conveyer is at rest; and means for periodically advancing the conveyer through the same number of spaces between the holders as there are lifts in the heel-section. 105

2. A heel building machine for forming heel-sections of at least two lifts having, in 110 combination, a frame providing a number of lift-receiving stations equal to the number of lifts in the heel-section and a discharge station; a conveyer provided with a number of lift-holders equal to one more 115 than a multiple of the number of lifts in the heel-section to be formed, an equal number of said holders registering with said receiving and discharge stations when the conveyer is at rest; means for periodically advancing the conveyer through the same number of spaces between the holders as there are lifts in the heel-section; and means at the discharge station for ejecting the heel-sections delivered thereto. 120

3. A heel building machine for forming heel-sections of at least two lifts having, in combination, a frame providing a number of lift-receiving stations equal to the number of lifts in the heel-section and a discharge 130

- station; a conveyer provided with a number of lift-holders equal to one more than a multiple of the number of lifts in the heel-section to be formed, an equal number of 5 said holders registering with said receiving and discharge stations when the conveyer is at rest; means for periodically advancing the conveyer through the same number of spaces between the holders as there are lifts 10 in the heel-section; a heel-section holder at the discharge station; and means cooperating therewith to transfer to said holder each heel-section delivered to the discharge station.
- 15 4. A heel-building machine for forming heel-sections of at least two lifts having, in combination, a frame providing a number of lift-receiving stations equal to the number of lifts in the heel-section and a discharge station; a conveyer provided with a number of lift-holders equal to one more than a multiple of the number of lifts in the heel-section to be formed, an equal number 20 of said holders registering with said receiving and discharge stations when the conveyer is at rest; means for periodically advancing the conveyer through the same number of spaces between the holders as there are lifts in the heel-section; means for securing together all the lifts of the heel-section; and means at the discharge station for ejecting the completed heel-section.
- 30 5. A heel building machine for forming heel-sections of a plurality of lifts having, in combination, a rotary turret provided with peripheral lift-holding pockets equal in number to at least twice the number of lifts in the heel-section being formed plus one; a frame providing lift-receiving stations, 35 equal in number to the number of lifts in the heel-section, lift-pasting stations equal in number to one less than the number of lifts in the heel-section, and a heel-section discharging station, all arranged in circular series and past which said turret pockets are moved; and means for advancing said turret step-by-step in steps of such angular length that a lift delivered to a pocket at a certain receiving station traverses all of said stations in such order that it registers with the discharge station only at the final step.
- 45 6. A heel building machine for forming heel-sections of a plurality of lifts having, in combination, a rotary turret provided with peripheral lift-holding pockets equal in number to twice the number of lifts in the heel-section plus one; a frame providing lift-receiving stations, equal in number to the number of lifts in the heel-section, lift-pasting stations equal in number to one less than the number of lifts in the heel-section, and a heel-section discharging station, all arranged in circular series and past which said turret pockets are moved; and means 50 for advancing said turret step-by-step in steps of such length that lifts deposited at all the receiving stations except one are delivered to a pasting station before being delivered to the discharge station.
- 60 7. A heel building machine for forming heel-sections of n lifts having, in combination, a rotary turret provided with $2n+1$ peripheral pockets; a frame providing n lift-receiving stations spaced to register with the same number of consecutive pockets on the turret, and with a discharge station spaced from a certain receiving station to register with the n th pocket therebeyond counting in the direction the turret rotates;
- 65 8. A heel building machine for forming heel-sections of a plurality of lifts having, in combination, a frame providing a plurality of lift-receiving, lift-pasting and discharge stations, equal in number to twice the number of lifts in the heel-section all arranged in an endless series; lift conveying mechanism providing a series of lift-holders equal in number to one more than the number of said stations and movable in a closed path past said stations; and means for advancing said lift-holders step-by-step through a plurality of said stations at each step equal to the number of lifts in the heel-section.
- 90 9. A heel building machine for forming heel-sections of a plurality of lifts having, in combination, a frame providing a plurality of lift-receiving, lift-pasting and discharge stations, equal in number to twice the number of lifts in the heel-section all arranged in an endless series; lift conveying mechanism providing a series of lift-holders equal in number to one more than the number of said stations and movable in a closed path past said stations; and means for advancing said lift-holders step-by-step through a plurality of said stations at each step equal to the number of lifts in the heel-section.
- 95 10. A heel building machine for forming heel-sections of n lifts having, in combination, a rotary turret provided with $2n+1$ peripheral pockets; a frame providing n lift-receiving stations spaced to register with the same number of consecutive pockets on the turret, and with a discharge station spaced from a certain receiving station to register with the n th pocket therebeyond counting in the direction the turret rotates;
- 100 110 115 120 125 130

and means for periodically advancing said turret in steps equal in angular extent to n spaces between said pockets, whereby all lifts received at said certain lift-receiving station are delivered directly to said discharge station.

11. A heel building machine for forming heel-sections of n lifts having, in combination, an endless carrier presenting $mn+1$ receptacles for holding lifts; a device registering with one of said receptacles when the carrier is at rest for discharging the lifts held therein; means for advancing the carrier step-by-step through n spaces between said receptacles; and means for operating said lift discharging device at each period of rest.

12. A heel building machine for forming heel-sections of n lifts having, in combination, an endless carrier presenting $mn+1$ receptacles for holding lifts; a device registering with one of said receptacles when the carrier is at rest for discharging the lifts held therein; lift pasting devices adjacent $n-1$ of said receptacles when the carrier is at rest; means for advancing the carrier step-by-step through n spaces between receptacles; and means for operating said lift discharging and pasting devices at each period of rest.

13. In a heel building machine of the character described, a turret having a series of peripheral lift-holding pockets; an ejecting device to which said pockets are serially presented; and means to rotate said turret in steps of such angular extent that one or more pockets are caused to traverse said ejecting device before the turret is brought to rest with a pocket in registry therewith.

14. In a heel building machine of the character described, a frame presenting an opening through which heels are discharged; a turret having a series of lift-holding pockets movable past said opening as the turret is rotated; means for rotating said turret in steps of such angular extent that one or more pockets are caused to cross said opening before the turret is brought to rest with a pocket registering with said opening; an ejecting device in registry with said opening; and means to operate said device at each period of rest of said turret.

15. In a heel building machine of the character described, a rotary turret having a series of lift-holding pockets; a discharge opening in the supporting frame in the path of movement of said pockets and with which a pocket registers at each period of rest of the turret; means for rotating said turret in steps of such length that at least one pocket is caused to cross said opening at each step; means to close said opening during said passage; and means for ejecting

the heel in the pocket registering with said opening at each period of rest.

16. In a heel building machine of the character described, a turret having a series of peripheral lift-holding pockets movable past a discharge opening in the supporting frame; means for rotating said turret intermittently to bring said pockets serially in registry with said opening but in steps of such length that at least one pocket traverses said opening at each step; means for ejecting the heel in the pocket at said opening at each period of rest; and means controlled by said ejecting means for closing said opening while the turret is rotating.

17. In a heel building machine of the character described, a turret having a series of peripheral lift-holding pockets movable past a discharge opening in the supporting frame; means for rotating said turret intermittently to bring said pockets serially in registry with said opening but in steps of such length that at least one pocket traverses said opening at each step; and means for preventing the discharge of any heel through the opening except when the turret is at rest.

18. In a heel building machine of the character described, a turret having a series of peripheral lift-holding pockets movable past a discharge opening in the supporting frame; means for rotating said turret intermittently to bring said pockets serially in registry with said opening but in steps of such length that at least one pocket traverses said opening at each step; means for insuring the passage of said pocket across said opening without loss of the heel therefrom; and means for discharging the heel from each pocket registering with said opening at the periods of rest.

19. In a heel building machine of the character described, a turret having a series of peripheral lift-holding pockets movable past a discharge opening in the supporting frame; means for rotating said turret intermittently to bring said pockets serially in registry with said opening but in steps of such length that at least one pocket traverses said opening at each step; a plunger registering with said opening; means for reciprocating said plunger at each period of rest to discharge the heel then in registry with said opening; a cover plate for said opening; and means connecting said plate and plunger-actuating mechanism operating to retract the plate when the plunger advances and advance the plate when the plunger is retracted.

20. A heel building machine having, in combination, a carrier for transferring lifts from a receiving station to pasting and ejecting stations, a plurality of pockets on

said carrier for supporting lifts, means for intermittently advancing said carrier in steps of such length that at each period of rest a pocket is opposite each of said stations, and means at said stations for pasting and ejecting the lifts thereat operated in time relation to the movement of the carrier.

21. A heel building machine having, in combination, a carrier for transferring lifts from a receiving station to pasting and ejecting stations, a plurality of pockets on said carrier for supporting lifts, means for intermittently advancing said carrier in steps of such length that at each period of rest a pocket is opposite each of said stations, a paste pot at said pasting station located adjacent the path of movement of the carrier, means operating during said periods of rest for transferring paste from said pot to the exposed lift in the pocket then at the pasting station, and means at the ejecting station for discharging said pasted lift at a subsequent period of rest of said carrier.

22. A heel building machine having, in combination, a carrier for transferring lifts from a receiving station to pasting and ejecting stations, a plurality of pockets on said carrier for supporting lifts, means for intermittently advancing said carrier in steps of such length that at each period of rest a pocket is opposite each of said stations, a pasting mechanism comprising a movable paste pad at said pasting station, an ejecting plunger at said ejecting station, and means for operating said pad and plunger at each period of rest to paste and eject the lifts in the pockets then at said stations.

23. A heel building machine having, in combination, a carrier for transferring lifts from a receiving station to pasting and ejecting stations, a plurality of pockets on said carrier for supporting lifts, means for intermittently advancing said carrier in steps of such length that a lift pocket transferred from a receiving to a pasting station is thereafter transferred to another receiving station before being delivered to said ejecting station.

24. A heel building machine having, in combination, a carrier presenting a series of lift-holding pockets arranged in a closed path and movable to transfer said pockets along said path, means for advancing said pockets in successive steps of equal length, and lift-receiving, pasting and ejecting stations so located adjacent the path of movement of the carrier that a lift placed in a pocket at a selected receiving station will be transferred to all the remaining pasting and receiving stations before being delivered to said ejecting station.

25. A machine for building a heel having n lifts having, in combination, $mn+1$ lift-holding pockets arranged in a closed path, a carrier for said pockets movable step-by-

step past n lift-receiving stations, $n-1$ pasting stations, and one ejecting station arranged adjacent said path and to each of which a pocket is presented at each period of rest, and means for advancing said carrier in steps equal to the spacing of n pockets, said receiving, pasting and ejecting stations being so related that a pile of n lifts comprising $n-1$ pasted lifts is received in each pocket before coming to rest at said ejecting station.

26. In a heel building machine, a heel-carrier comprising a base disk, four other disks supported thereby, and lift-holding pockets at the periphery of said carrier comprising two back engaging arms and two breast engaging arms, said arms being connected each to one of said other four disks.

27. In a heel building machine, a heel-carrier comprising a disk, lift-holding pockets at the periphery thereof each composed of two pairs of relatively movable arms arranged to grip the lift edge at its breast and back, and means supported by said disk for adjusting the relation of said arms to accommodate lifts of different sizes.

28. In a heel building machine, a heel-carrier comprising a base disk, a pair of disks carried by said base disk and rotatable thereon in opposite directions, a series of pairs of arms projecting radially from said pair of disks one arm of each pair connected to one disk and the other arm of each pair connected to the other disk, a second pair of rotatable disks mounted on the base disk having similar pairs of arms connected thereto in like manner and cooperating with said other pairs to form lift holding pockets, and means for rotating the disks of said pairs in opposite directions to cause said arms to open and close relative to each other.

29. The method of building pasted heel-sections composed of n lifts which comprises supplying n lifts in serial order at n receiving stations; advancing said lifts in such order to an ejecting station and to $n-1$ pasting stations; ejecting and pasting the lifts at said stations and simultaneously supplying another series of n lifts at the receiving stations; advancing said new series in like manner and simultaneously advancing $n-1$ pasted lifts to said receiving stations; ejecting, and pasting, and supplying another new series of n lifts, as before; advancing said last series in like manner and simultaneously advancing $n-1$ pasted lifts to said receiving stations; and continuing said supply, advance and pasting operations whereby each heel-section ejected during the pasting operation is composed of $n-1$ contiguous pasted lifts and one unpasted lift on top.

30. The method of building pasted heel-sections composed of n lifts which comprises

successively delivering $n-1$ pasted lifts at $n-1$ of a series of n lift-receiving stations; successively depositing an unpasted lift on each of said exposed pasted lifts and an additional unpasted lift at the n th receiving station; and successively ejecting each heel-section when n lifts have been so assembled.

31. The method of building heel-sections composed of n lifts which comprises successively delivering $n-1$ partially completed heel-sections at $n-1$ of a series of n lift-receiving stations; adding a lift to each of said heel-sections, and simultaneously depositing a lift at the n th lift-receiving station; the receiving stations to which said partially completed sections are delivered being always the same stations of said series; and ejecting each section that is built to n lifts.

32. The method of building pasted heel-sections composed of n lifts which comprises providing n lift-receiving stations; maintaining at least one pasted lift at $n-1$ of said receiving stations; successively adding other lifts to said pasted lifts and simultaneously supplying a lift at the empty n th receiving station, and meanwhile intermittently advancing said pasted lifts to other stations and back to the receiving stations except when the addition of one lift makes n lifts in the heel-section whereupon said heel-section is ejected.

33. A heel building machine for forming heel-sections of n lifts having, in combination, an endless carrier presenting $mn+1$ receptacles for holding lifts; a device registering with one of said receptacles when the

carrier is at rest for discharging the lifts held therein; means for advancing the carrier step-by-step through n spaces between said receptacles; and a tube-like heel-press for receiving the discharged heel-sections and holding them under pressure.

34. A heel building machine for forming heel-sections of n lifts having, in combination, an endless carrier presenting $mn+1$ receptacles for holding lifts; a device registering with one of said receptacles when the carrier is at rest for discharging the lifts held therein; lift pasting devices adjacent $n-1$ of said receptacles when the carrier is at rest; means for advancing the carrier step-by-step through n spaces between receptacles; and a tube-like heel-press, having side members yieldingly pressed inward, into which each pasted heel-section is discharged and forced therethrough under pressure by the succeeding heel-section discharging operations.

35. A machine for building a heel having n lifts having, in combination, $mn+1$ lift holding pockets arranged in a closed path, a carrier for said pockets movable step-by-step past n lift-receiving stations, $n-1$ pasting stations, and one ejecting station arranged adjacent said path and to each of which a pocket is presented at each period of rest, a plunger at the discharge station for ejecting the piles of pasted lifts delivered successively to the discharge station, and a tube-like heel-press for receiving and holding the piles as they are ejected.

ERASTUS E. WINKLEY.
